Filed Oct. 17, 1958, Ser. No. 767,872

4 Claims. (Cl. 46—29)

This invention relates to a toy building construction and more particularly to a construction which may be erected from structural elements, many of which are of substantially identical form and frictionally secured together whereby the use of tools may be avoided and the structural elements readily assembled and disassembled.

More particularly it is contemplated by the present invention to provide a building structure having vertical and horizontal beams upon which may be supported substantially plane flat wall or siding elements to close in the resulting building, these wall elements being supported from certain of the beams and adapted to have overlapping edges so as to form a closed structure.

The beams or stringers forming the skeleton of the structure may be of substantially identical form, these elements as illustrated being of I-beam construction in cross section (although this is not essential in all aspects of the invention) and at the ends of these elements are secured connector blocks having recesses therein of generally T-shaped form in cross section opening through the end faces of the blocks whereby T-shaped connector elements may be employed to connect one beam to an adjoining beam.

The faces of the connector blocks are provided, in addition to the T-shaped recesses, with rectangular recesses at substantially their central portions to permit the connection of one element with another extending at right angles thereto by the T-shaped members as will be hereinafter described. The flanges of the I-beam elements are provided with openings or slots adapted to receive tongues or similar projecting members provided upon the flat sheet-like wall elements to support the latter.

As will be hereinafter explained, the various parts of the structure may be secured together in a number of different ways to form a building structure, for example, which will be provided with closed end walls, the beam elements comprising the skeleton of the structure being frictionally secured together without the use of tools.

One object of the present invention is to provide a novel toy building construction, the parts of which may be readily and easily assembled.

Still another object of the invention is to provide a toy building construction comprising a plurality of construction elements which may be frictionally secured together in a number of different arrangements without the use of tools and which parts may be readily detached when desired.

A still further object of the invention is to provide a toy building construction comprising a plurality of beam-like supported elements from which a main frame of a building or like structure may be erected and by which wall plates may be supported to form a closed building.

To these and other ends the invention consists in the novel features and combinations of parts to be herein-after described and claimed.

2

In the accompanying drawings:

Fig. 1 is a side elevational view of a portion of a building structure embodying my invention;

Fig. 2 is a sectional view on line 2—2 of Fig. 1;

Fig. 3 is an exploded perspective view of a number of beam-like stringers or elements adapted for frictional connection to form a relatively rigid structure; and

Fig. 4 comprises a side elevational view and plan view of one of the T-shaped connector elements.

10 To illustrate a preferred embodiment of my invention I have shown in Fig. 1 of the drawings a building structure comprising a plurality of vertically disposed studs or beams 10 and a plurality of horizontal stringers 11, these members being frictionally secured together as will be hereinafter explained. The members 10 and 11 are of I-beam construction as shown in the sectional view of Fig. 2 having web portions 12 and upper and lower flanges 13 and 14. The upper flanges 13 are provided with openings 15 at spaced intervals for a purpose to be hereinafter described.

15 As shown in Fig. 3 of the drawings, connector blocks 16 and 17 are secured to the ends of the beam members or stringers 10 and 11, it being understood that one of these connector blocks will be secured to each end of the members 10 and 11. The blocks 16 and 17 are of rectangular shape and may be of equal length and width if desired if the flanges on the I beams are of the same dimension as the height thereof, it being desired that 20 the connector blocks be of the same dimensions in length and width as the I beams as illustrated. The parts thus described may be made of any suitable material such as plastic, for example, and the connector blocks will be rigidly secured to the beams, or formed integrally therewith.

25 30 35 The connector blocks 16 and 17 are of identical form but are given different numerals to facilitate the explanation of the manner in which they may be secured together. Each of the connector blocks is provided with a number of recesses opening through the end face thereof. Certain of these recesses indicated at 18 are of T-shaped form in cross section and not only open through the end faces of the blocks 16 and 17, but also open through the side faces thereof, as shown at 19. In 40 addition, a central rectangular opening 20 is provided at substantially the central portion of the end face of each of the blocks 16 and 17.

45 50 55 Connector elements are provided, as shown in Fig. 4, which are also of substantially T-shaped form in cross section. Each of these connector elements has a head 22 and a stem 23 projecting therefrom, the head being of substantially rectangular form as shown, and the stem being of rectangular form in cross section, its long dimension being parallel to the long dimension of the head 60 so that the overhanging portion of the head is substantially the same width upon all sides of the stem.

If it is desired to connect two of the beams 10 to form a vertical column, one being superposed upon another, this may be effected, as shown diagrammatically in Fig.

side face recess 19 of the upper block. As many of these T-shaped connecting blocks may be employed as desired to connect two of the beams 10 in vertical alignment in this manner. Usually, however, they will only be employed at the side faces where it is desired to connect horizontal beams.

When the T-elements have been inserted into the lower connector block 16, the upper beam may be placed downwardly upon it with the end faces of the connector blocks abutting and, as will be obvious, the T-shaped connector elements will be disposed half in the lower connector block and half in the upper connector block. As these T-shaped elements fit snugly in the recesses 18, they will frictionally hold the two beams together forming a vertical column.

Preferably the thickness dimension of the blocks, that is to say, the vertical dimension of the block 16 shown in Fig. 3, will be substantially half of the length of the blocks so that when it is desired to connect a horizontal beam 11 to a vertical column consisting of one or more beams 10, there will be no projecting edges and, if a horizontal beam is connected at each side of a vertical column, as shown in Fig. 1, for example, the upper and lower edges of the connector blocks will be in alignment.

If it is desired to connect a horizontal beam 11 to a vertical beam 10, one of the T-shaped connector elements 22 is placed in one of the recesses 18 of a connector block 16 as illustrated in dotted lines in Fig. 3 and as previously described. The stem 23 of the connector block will project outwardly through the recess 19 and from the end face of the connector block 16. This stem 23 may then be frictionally inserted into the recess 20 in the end face of the connector block 17. As the frictional fit will be a snug one, the horizontal beam 11 will be thus secured to one of the vertical beams 10. It will, of course, be understood that, if one of the T-shaped connector elements has been employed to connect two vertical beams into a column, this same element will be employed to connect a horizontal beam to a column thus formed. It will also be obvious from Fig. 2 that a horizontal beam may be connected at each of the four sides of a vertical column so that horizontal beams may extend from the column in any or all of the four directions.

To form the walls of the building sheet-like members 25 are provided as shown in Figs. 1 and 2. These members may also be formed of any desired sheet material such as plastic, and adjacent their upper ends may be provided with spaced rearwardly projecting hooks or lugs 26, the spacing of these members corresponding to that of the openings 15 in the flange portions of the I beams so that the hooks may be engaged in these openings and the members 25 thereby suspended. Preferably the length of these members 25 will be sufficient to extend between adjacent vertical columns when the latter are connected by the horizontal beams 11 as shown in Fig. 1. With this arrangement the joints between the wall members will lie at the center of the columns and thus a closed wall will result.

Similar hooks or lug members 27 may be provided at the lower edges of each of the members 25, which members will be offset rearwardly in order to engage behind the upper edge of the next lowermost element as shown more particularly in Fig. 2 and thus prevent outward swinging of the lower edges of these members. The

lug members 26 are displaced a slight distance below the upper edges of the members 25 so as to provide for this engagement of the members 27 with the edge of the members 25 above the lugs 26.

While I have shown and described a preferred embodiment of my invention, it will be understood that it is not to be limited to all of the details shown, but is capable of modification and variation within the spirit of the invention and within the scope of the claims.

What I claim is:

1. A toy building structure comprising a pair of beam elements and means for connecting the ends of said elements together, said connecting means comprising a connector block at the end of each beam having a substantially plane end face, each of said blocks being provided with T-shaped recesses at the edges thereof opening through its end face and also through the side faces adjacent said edges, and further provided with a recess rectangular in cross section adjacent the central portion of said end face, and a T-shaped connector element frictionally mounted in a T-shaped recess of the block at the end of one beam and the rectangular recess in the block at the end of the other beam.

2. A toy building structure comprising a pair of beam elements and means for connecting the ends of said elements together, said connecting means comprising a connector block at the end of each beam element having a substantially plane end face provided with T-shaped recesses therein which open through said face and also through the side faces of said member, said beam elements being disposed with said plane faces in abutting relation, a generally T-shaped connector having its head portion received frictionally in the recesses of said connector blocks at the end faces thereof and having its stem portion projecting through the side surfaces of said connector blocks.

3. A toy building structure comprising a pair of beam elements and means for connecting the ends of said elements together, said connecting means comprising a connector block at the end of each beam element having a substantially plane end face provided with T-shaped recesses therein which open through said face and also through the side faces of said member, said beam elements being disposed with said plane faces in abutting relation, a generally T-shaped connector having its head portion received frictionally in the recesses of said connector blocks at the end faces thereof and having its stem portion projecting through the side surfaces of said connector blocks, and a third beam element having a similar connector block at its end, the face of which abuts the side surfaces of the blocks on said first-mentioned beam elements and having an opening in its end face in which the projecting stem of said T-shaped connector element is frictionally received.

4. A toy building structure as in claim 2 wherein a third beam extends substantially transversely to said pair of beam elements from a position adjacent the abutting faces thereof, and wherein the stem of said T-shaped connector is secured to the end face of said third beam.
